Design No. 609 -

N. J. Pedder

Design of Cook Stove

Patented November 8, 1853

UNITED STATES PATENT OFFICE.

N. S. VEDDER, OF TROY, NEW YORK.

DESIGN FOR A COOKING-STOVE.

Specification forming part of Design No. 609, dated November 8, 1853.

To all whom it may concern:

Be it known that I, N. S. VEDDER, of Troy, in the county of Rensselaer and State of New York, have invented or produced a new and original Design of Cook-Stove, which I call the "Golden Rose"; and I do hereby declare that the following is a full, clear, and exact description of the same, reference being had to the annexed perspective drawing, making a part of this specification.

The description of my design of cook-stove is as follows, viz: A is the top plate with the molding b around the edge. B is the upper front plate with the doors P P and C C. P P are ornamented on the panels with the rosebud and leaf c c. D is the lower front plate with the raised panel e, and the flue-doors E E, ornamented with a leaf and rosebud, f, on the panels. F is the jamb-plate ornamented at the bottom with three panels, g g g, decorated with the rosebud and leaves h h h. j is a raised panel at the top of the jamb. G is the fire-door ornamented on the panel with a rose and leaves, k. H H are oven-doors ornamented on the panels with roses and leaves ll. J is the molding of the bottom plate. K is the leg ornamented with roses, leaves, and buds m. L is the hearth-plate.

Having thus described my new design of cook-stove, what I claim as new, and desire to secure by Letters Patent, is—

The ornamental design and configuration of cook-stove plates such as herein described, and represented in the annexed drawing.

N. S. VEDDER.
